UNITED STATES PATENT OFFICE.

PERLEY F. HAZEN, OF ST. JOHNSBURY, VERMONT, ASSIGNOR TO THE E. & T. FAIRBANKS & COMPANY, OF SAME PLACE.

DESIGN FOR A SCALE-BEAM-STAND MEMBER.

SPECIFICATION forming part of Design No. 33,000, dated July 24, 1900.

Application filed May 1, 1900. Serial No. 15,144. Term of patent 14 years.

To all whom it may concern:

Be it known that I, PERLEY F. HAZEN, a citizen of the United States, residing at St. Johnsbury, in the county of Caledonia, State 5 of Vermont, have invented and produced a certain new and original Design for a Scale-Beam-Stand Member, of which the following is a description, reference being had to the accompanying drawings, and to the letters of 10 reference marked thereon.

My invention relates to a new and original design for a scale-beam-stand member; and it consists in the matters hereinafter described, and referred to in the appended claim.

15 The invention is illustrated in the accompanying drawings, in which—

Figure 1 is a front view of an entire scale-beam-stand member embodying my design; and Fig. 2 is a top plan view of the base 20 member forming the essential feature of this design, the upper portion of the stand being shown in cross-section.

In the drawings, A represents as a whole one member of a scale-beam stand the upper part

of which is of usual form, while B is the lower 25 part. This base B has a general triangular-shaped portion at one end, from which the upper portion projects, two of the sides *a a* of the substantially-triangular portion being formed on a double set of compound curves 30 running toward the apexes *b b*, while from the two opposite apexes *b* the lines run in compound curves *c c* and merge into the parallel sides *d d*, which at their opposite ends are merged into the apex *e*.

35 The essential feature of the design consists in the base-piece of the shape and configuration shown.

Having thus described my invention, what I claim is—

40 The design for a scale-beam-stand member; substantially as shown and described.

In testimony whereof I affix my signature in presence of two witnesses.

PERLEY F. HAZEN.

Witnesses:

ALBERT L. FARWELL,
C. H. HORTON.
